UNITED STATES PATENT OFFICE.

JOSEPH M. SHULTS AND FREDERICK W. SHULTS, OF BALTIMORE, MARYLAND.

FLUID-BLAST STOKER.

1,109,367.

Specification of Letters Patent.

Patented Sept. 1, 1914.

Application filed August 22, 1912. Serial No. 716,474.

To all whom it may concern:

Be it known that we, JOSEPH M. SHULTS and FREDERICK W. SHULTS, citizens of the United States, residing at Baltimore, in the State of Maryland, have invented certain new and useful Improvements in Fluid-Blast Stokers, of which the following is a specification.

This invention relates to a fluid-blast stoker for feeding fuel into furnaces.

The object of the invention is to provide means which shall act automatically, whereby steam or air under pressure may be caused to make short, quick blasts at predetermined intervals, which blasts act directly against a small quantity of coal, or similar fuel, and thereby drive the said fuel into the furnace and distribute it over the fire bed.

One form of construction, for embodying the invention is illustrated in the accompanying drawing in which,

Figure 1 is an end elevation showing in section a part of a furnace, and in side view the improved fluid-blast stoker. Fig. 2 is a vertical section, on a larger scale, of the fluid-blast stoker.

The drawings show an apparatus operated by steam.

Referring to the drawing the letter, A, designates a furnace, which may be of any known construction. The brickwork, b, grate-bars, c, furnace door, d, ash-pit, e, and ash-pit door, f, are indicated to more clearly explain the application of the fluid-blast stoker and its relation to the furnace. A suitable stationary fuel chute, 1, receives a charge of coal, coke, or other fuel from an elevated supply (not shown) and this chute inclines downwardly and its lower end enters the furnace at the front. It is immaterial how the connection of the lower end of the chute is made with the furnace front; in the present instance the chute is shown as being passed through the furnace door plate, d. The lower end of the chute may have a vertical curve, 3, that forms a depression in which small lumps of fuel may lodge and where said lumps may choke, or partly fill, the passageway of the chute. In the operation of this device, the fuel in the form of lumps will, by the action of gravity or otherwise, flow down the chute, 1, and accumulate in the curved depression, 3, and in the normal condition of this apparatus, just preceding a blast of fluid-

pressure presently to be described, the said curved depression will be full of fuel.

The improved means of the present invention comprises a cylinder, 4, having an internal bore, 5, and one end being closed by a head, 6, while the other end has a head, 7, to which the blast-pipe, 8, is attached; the hole or opening in this head constitutes a port, 9, within the cylinder is a valve, 10, which closes and opens said port, and this valve has a stem, 11, whose end fits in and has play in a guide bearing, 12. A piston, 13, is movable within the bore of the cylinder and this piston has a central hole, 14, which allows certain free movement of the piston on the valve-stem, 11. The valve-stem carries a collar, 15, that is secured rigidly to the stem by a screw, 16. This collar may be adjusted along the stem to such position as will cause the proper co-action of the piston, 13, and valve, 10. Two cushion springs, 17, and, 18, in the form of spirals, on the valve-stem, 11, and the piston, 13, has position between the said two springs. One spring, 17, serves as a cushion between the valve, 10, and the piston, and the other spring, 18, serves as a cushion between the collar and the piston. The blast-pipe, 8, leads from the hole in the cylinder-head, 7, where the valve-port is located, and said pipe enters the fuel chute, 1, at the outer side of the curved depression, 3, as seen in Fig. 1.

In the operation of this device the piston has a reciprocating movement to close and open the valve, 10; the piston is moved in the direction to close the valve by a power spring, 19, which is under compression between the piston and the cylinder head, 6. The piston will be moved in the direction to open the valve by the action of fluid-pressure entering the cylinder through a pipe, 20; this fluid pressure will fill the space, 21, in the cylinder and create a preponderance of pressure on that side of the piston that will overcome the pressure on the opposite side caused by the spring, 19, and move the piston and momentarily open the port, 9, thereupon fluid in the space, 21, will escape through the port in the form of a puff and will pass through the pipe, 8, and cause a quick short blast of fluid to enter the chute, 1, and such blast, acting directly against the lumps of fuel seated in the curved depression, 3, of the chute, will drive the fuel into the furnace and distribute the lumps or scatter it over the bed of heated coals. As

soon as this small quantity of fuel has been blown from the depression, 3, into the furnace, another like small quantity will automatically move downwardly in the chute, 1, and take position in the depression, 3, ready for another blast. The instant the valve, 10, is unseated by the preponderant pressure of fluid, the fluid in the chamber, 21, escapes through the open valve-port, 9, and such escape, of course instantly reduces the pressure on that side of the piston causing the preponderance of pressure to shift to the opposite side of the piston where the power spring, 19, is acting, and this spring then moves the piston back until it contacts with the cushion spring, 17, and valve, 10, and seats the latter. This operation of moving the piston, 13, one way by fluid, and simultaneously opening the valve-port, 9, and giving a fluid blast into the fuel chute, 1, and then moving the piston in the reverse direction by the pressure of the spring and closing the valve-port, is repeated automatically.

25 It will be seen that we have herein disclosed means, which when set for action will automatically produce short, quick blasts of compressed fluid each blast succeeded by an interval and each blast acting on a small 30 charge of fuel contained in the chute and drive such fuel into the furnace.

It is to be understood the fluid-blast stoker may produce blasts of steam, or blasts of air, and that the device is operable by either kind 35 of fluid; ordinarily the steam will be more convenient to use.

Having thus described our invention what we claim and desire to secure by Letters Patent is:—

40 1. In a stoker for automatically feeding charges of fuel to furnaces by the action of

short, quick blasts of compressed fluid, the combination of a chute for conveying fuel into a furnace; a cylinder having an outlet port; a blast pipe communicating from the outlet port to the said chute; a valve controlling said outlet port and provided with a stem which has central position within the cylinder; a piston reciprocable in the cylinder and having a central hole which allows certain free movement of the piston on the valve-stem and said piston moving the valve to open and close said port; a power spring pressing on one side of the piston and serving to move the piston in the direction that will close the said valve; and a pipe opening into said cylinder for supplying fluid-pressure that will act on the piston and move the latter in the direction that will open the said valve. 60

2. A stoker for feeding fuel to furnaces by blasts of fluid under pressure, comprising the combination of a fuel chute in which the charge of fuel is to be seated; a fluid-pressure cylinder having an outlet port; a valve controlling said outlet port and having a stem provided with a collar that is adjustable longitudinally along said stem; a piston movable in the cylinder and having a central hole through which loosely passes that part of said valve-stem that is between the valve and the said collar; means to supply fluid-pressure to the cylinder to operate the piston, and a blast-pipe communicating from the said outlet port to the fuel chute. 75

In testimony whereof we affix our signatures in presence of two witnesses.

JOSEPH M. SHULTS.

FREDERICK W. SHULTS.
